EXCAVATING DIPPER CONSTRUCTION

William H. Brune, Chicago Heights, Ill.

Application February 19, 1931, Serial No. 516,884

8 Claims. (Cl. 214—145)

This invention relates to excavating implements of the kind which are usually constructed with a forward or upper open end, designed to develop efficiency in digging and with a rear end closed by a movable door, which said implements are usually manipulated by power applied through the medium of a directing stick and flexible lifting connections, and called dippers.

10 The object of the invention is to improve the construction of such an implement, and particularly that portion thereof which is concerned with the movable door, the means for mounting said door and the elements of control upon the body of the dipper; the construction of the latch through which the door is releasably held in closed position; and the designing of the latch keeper in a manner to protect it from injury and at the same time adapt it to serve as a picking blade for raking material from a disadvantageous position to a position in which it is more accessible to the scooping action of the dipper.

15 The invention proceeds upon the principle of having the door, as well as the confines of the rear opening of the dipper which it closes, constructed with a deflection at an intermediate horizontal line, at a substantial angle that will cause the contents of the dipper to dump more readily and to begin to discharge more promptly than with doors heretofore constructed; also in having hinges through which the door is mounted upon the dipper constructed with characteristic sections affording stiffness transversely of the hinges, and secured through the medium of flanges on these hinges to flanges integral with the door, transverse abutting faces being likewise provided on the door and hinges, and the several meeting faces being suitably riveted together; having the hinges of the door and flexibly connected controls united to the body of the dipper through means of hinges, the butts of which comprise cylindrical enlargements on the body of the dipper, with a pintle opening therethrough and with channels cut transversely through the butts and intersecting the pintle openings to receive the hinging ends of the parts that are to be connected; having a novel construction of door latch characterized by a controlling lever pivoted upon a threaded strut, longitudinally adjustable in a direction which changes the initial or locking position of the latch bolt; and having the keeper for the latch constructed with a picking spade extending sufficiently beyond the confines of the keeper to pre-

vent impact of the latter with destructive materials that are to be attacked through the dipper, and presented in such relation to the heel of the dipper as to permit of its being used as a pick when the dipper, in upstanding position, is manipulated in a downward and inward direction.

5 In the accompanying drawings—

10 Figure 1 is a side elevation, and Figure 2 a bottom plan view of a dipper embodying the several features of the present invention; the replaceable teeth of the dipper (shown in Figure 1 but having no bearing upon the present invention) being omitted in Figure 2.

15 Figure 3 is a rear elevation of the door, its hinges (minus their bearing ends) and the latching mechanism.

20 Figure 4 is a top plan view of the body of the dipper showing particularly the integral barrel-like butts formed thereon and channelled for the admission of parts that are to be pivotally connected therewith through the medium of pintles (not shown).

25 Figure 5 is an elevational view of the front open end of the dipper showing the bail ears and one of the integral channelled butts through which hinging connections are made.

30 Figures 6 and 7 are, respectively, a face view and an edge view of the dipper bail, the former including one of the pivotal connections of the bail and a portion, in section, of one of the bail attaching ears.

35 Figure 8 is a detail view of one of the bail pintles.

40 Figures 9 and 10 are two views, as seen in directions at right angles to each other and on a greatly enlarged scale, of the means which secures the bail pintle in place.

45 Figure 11 is a section on the line 11x—11x of Figure 3.

50 Figure 12 is a section on the line 12x—12x of Figure 3.

55 Figure 13 is a section on the line 13x—13x of Figure 12.

60 Figure 14 is a section of the latch lever on line 14x—14x of Figure 3, minus parts associated therewith in Figure 3.

65 Figure 15 is a section through a portion of the dipper door, taken on the line 15x—15x of Figure 3 and omitting the adjustable pivoting strut intended to be mounted therein.

70 Figure 16 is a section through the bail attaching ear, taken on the line 16x—16x of Figure 1 and omitting the bail and its pintle.

75 Figure 17 is a section on the line 17x—17x of Figure 11.

Figure 18 is a section on the line 18x-18x of Figure 3, and

Figure 19 is a section on the line 19x-19x of Figure 1.

- 5 Referring more particularly to Figures 1 to 5, inclusive, A represents the body of a dipper with which the several features of the present invention are to be combined, which said body is shown constructed with a digging lip B armed 10 with replaceable point teeth C, a lifting bail D, dipper stick E pivoted to the body A at F and angularly controlling the body through means of a link G pivoted to the body at H and to the stick at I, and a door K pivoted to the body at L through hinges M and secured in closed position by latch N.

Except for the novel structural conditions hereinafter disclosed, and except for the novel construction of the replaceable tooth C which 20 combines with a dipper body A through the medium of undercut channels C', confining straps C2 and rivets C3, as described in my co-pending application, Serial No. 426,208, the parts thus far described may be of known general arrangement and function.

According to the present invention, the wall 1 of the door K and the confines 2 of the rear open end of the body A, are designed, respectively, with substantial deflections 3, 4, which 30 cause the lower portions of said door and confines to meet in a plane which has a downward and rearward inclination; or when the upper portion of the confine 2 and the corresponding portion of the door wall 1 are downwardly and rearwardly inclined, as shown in Figure 1, these 35 lower portions of said members lying below the deflections 3 and 4 are inclined rearwardly to a greater angle. The effect of so deflecting a substantial portion of the free end of the door 40 is to enhance the dumping effect and the promptness with which the dipper is evacuated when the door is released, besides causing that area of the contained mass which lies toward the free end of the door to begin to move in 45 advance of the remainder of the body of mass, and thus make for a more successful evacuation than when the entire mass is retarded until the door reaches a relatively wide angle, in which latter case the mass, when of a sticky, clayey 50 nature, tends to wedge between the walls and retard evacuation. With a door shaped in principle as illustrated, the less inclined portion of the door, at the beginning of the opening movement, exerts greater retardation against the 55 mass than the portion of greater inclination which is toward the free end of the door. Another advantage of the described design of door is that it adds to the capacity of the dipper without a corresponding increase in the overall 60 fore-and-aft dimensions in that wall of the dipper to which the controls are pivoted.

In order to provide pivotal connections for the door hinges and other controls which are to be mounted upon the rear wall of the dipper, said body is provided with one or more 65 pintle butts 5, 5a and 5b, preferably cast integrally with the dipper body, having bores 6, 6a and 6b for the reception of the pintles F, H, I and L, and having transverse channels 7, 7a and 7b providing seats for the hinge knuckles 8, stick knuckles 9 and link knuckles 10 which present said knuckles in positions to be intercepted by their respective pintles. Intermediate of the knuckle seats 7, 7a, 7b on the respective hinging butts, are minor transverse chan-

nels 11, 11a and 11b for the introduction of cotters, keys or the like for securing the several pintles against longitudinal displacement after the parts are assembled.

Hinges M are constructed with flanged sections, for instance, the T-section shown (Figures 17 and 18), or other section affording an attaching flange 12, and through means of said flange the hinges are riveted to upstanding bracket flanges 13, preferably braced as shown 10 at 14, formed on the door plate 1; these overlapping flanges 12 and 13 being firmly united by rivets 15, as shown. In addition to the long longitudinal abutting faces through which the 15 hinges and the door are united and which are approximately coextensive with the radius through which the door acts, these hinges have transverse positioning flanges 16 through which they abut against the inner marginal confine 17 of the door plate 1, to which they are riveted as at 18.

The integral attaching flanges 13, with their bracing brackets 14 and the riveted flanged hinges M, lend great stiffness to the plate 1 of the door, and this plate is additionally stiffened by the marginal flanges 17, 17a, which are perpendicular to the plate 1, and by horizontal strutting flanges 19 (see Figure 3).

It will be noted that the flanges 17, 17a, standing forwardly outward from the wall plate 30 1 of the door and in perimetric positions coinciding with the confines 2 of the rear open end of the body A, define with the door plate 1, a cavity that adds its capacity to that of the dipper; the said outstanding flanges also restrict lateral spill of the material; the cavity, during its rearward swing, develops suction upon sticky material filling the said cavity at the time of dumping, thereby lending initial assistance to evacuation; and the flanges lend rigidity to the door in addition to that bestowed by the flange-like hinging members which stand integrally outward from the rear face of the door plate. It will also be noted, with respect to the inwardly presented cavity of the door, 40 that its side walls at their lower face swinging portions, as also do the side confines of the discharge opening, partake of the rearward angular deflection of the door plate, and said door walls diminish to zero at the swinging end of the door so that the door plate lies directly against the body wall at the extreme swinging end of the door.

The latching mechanism of the door comprises a bolt 20, its housing box 21 and latch lever 22 fulcrumed at 23 on fulcrum strut 24 comprising a fixed bolt adjustably secured by nuts 25 in the lugs 26. Lever 22 carries pin 27 through which it engages in one or the other of the holes 28 in the upper end of said bolt 20. The free end of said lever 22 works behind the arcuate confining guide 29. Fulcruming pin 23 and bolt engaging pin 27 are held in place, respectively, by cotters 23a and 28a inserted through upstanding projections 23b and 28b 65 on the lever 22 and overlying the outer ends of said bolts. Bolt housing 21, as shown in Figures 12 and 13, comprise base 21a, guide walls 21b and cover plate 21c, which is secured not only by bolts 21d but by a tongue and groove 70 connection 21e as shown in Figure 13.

The latch keeper 20a is in the form of a hoe or broad picking blade protruding from the bottom wall of the dipper in position to serve the function of a pick or hoe for scraping ma- 75

terial from a relatively inaccessible position to a position where it may be picked up by the dipper, and this blade 20a has a socket 20b in position to receive the bolt 20 of the latch.

- 5 For the purpose of mounting the bail D upon the dipper body, the latter is provided with integral ears 30, the opposite faces of which are fashioned to receive into bearing the faces 31 on the inner members 32 of the bifurcated bail ends, while the outer surfaces of said ears are recessed to receive into bearing the protruding studs 33 integral with the inner faces of the outer members 34 of the bifurcated ends of the bail. The bail and bail ears being given 10 the construction as just described, the ends of the bail may be articulated with the bail ears and the body of the dipper by means of pintles 35 having enlarged ends 36 which afford radial bearings for the inner members 32 of the bifurcated bail ends, while the shoulders formed by 15 said ends 36 enter into longitudinal bearing against the bail ears, and the shank 37 extends through radial bearing stud 33 on the outer member of the bifurcated bail end and receives in its neck 39 the split washer 40 (shown on an 20 enlarged scale in Figures 9 and 10) that provides the outer shoulder on the pintle and prevents displacement of the bail on its articulation.

25 I claim:

1. An excavating dipper having a rear discharge opening and a door constructed with hinging means adapting it to swing to open and close said opening; said door having its portion 30 which lies nearer to its axis of hinging movement and its portion which lies nearer to its end which swings in the opening movement substantially straight from side to side but in two planes, at a substantial angle one to the other, thereby developing in said door a substantial 35 arch through which the door supports the load within the dipper, and whereby, in swinging to open position, the door affords more effective release of the contents of the dipper; the lateral confines of the rear discharge opening through 40 which the body receives the door when closed, lying in planes conforming to those of the door.

- 45 2. In an excavating dipper having a discharge opening, and a door for closing said opening, hinges through which the door is mounted upon the dipper, means for mounting said hinges upon said door comprising a flange on the door upstanding from the plane of the door, a flange on the hinge overlapping the lateral face of 50 said flange on the door, and rivets or the like passing through the overlapped portions of and securing said flanges together.

- 55 3. An excavating dipper having a discharge opening and a door for closing said opening, means for mounting the door upon the dipper comprising a flange upstanding from the surface of the door, a hinge pivoted upon the dip-

per and constructed with a T-section, with the web that forms the stem of the T lapping upon the lateral face of and riveted to the flange on the door.

4. An excavating dipper as described in claim 5, in which the hinge also has a transverse flange substantially perpendicular to the longitudinal axis of the hinge and to its overlapping flange, and the door has a face receiving said transverse flange.

10 5. In an excavating dipper having a discharge opening, a door for closing said opening constructed with hinge attaching flanges, brackets projecting perpendicularly from and sustaining said flanges laterally, and hinges having webs 15 overlapped upon and riveted to lateral faces of said flanges whereby the webs of the hinges are also positioned perpendicularly to said brackets.

20 6. In an excavating dipper, a door hinge and a cylindrical pintle butt formed integral with, extending across and strengthening the back of the dipper, channeled transversely through its pintle bearing but not entirely through the butt and leaving lateral bearing faces for the hinge, 25 an articulating bearing carried by said hinge, fitting between said bearing faces, and a pintle in said butt passing through said hinge, sustained by said butt against bending and limiting the forces imposed by the hinge upon the 30 pintle to stresses in shear.

7. In an excavating dipper, means for establishing an articulated connection with said dipper, comprising an integral cylindrical butt providing a strengthening rib extending across the 35 back of the dipper, provided with a pintle bore and having transverse channels extending partially through it intersecting said bore.

8. In an excavating dipper, a front or digging wall, a back wall and two side walls, all of 40 which walls extend approximately parallel to the digging axis of the dipper and are assembled as confines of a dipper body having a forward open charging end and a rear discharge opening, and a door approximately transverse to said digging axis, hinged to the back wall and peripherally conforming to the confines of and swinging to open and close the said rear discharge opening, the said door being provided on both faces with upstanding stiffening ribs; 45 those ribs on the inner face of the door being located at its side margins and extending forwardly to meet confines of the said rear opening, thereby adding capacity to the dipper; and a substantial portion of the door remote from its hinging points, together with corresponding portions of the forwardly presented marginal walls and side walls of the body, being deflected at a substantial angle rearwardly to the remainder of the door and reducing obstruction of 50 55 the door to discharge of the contents.

60 WILLIAM H. BRUNE.
